CLAIM

The ornamental design for an intelligent access control device, as shown and described.

DESCRIPTION

1. Intelligent access control device

Figure 1.1 is a front perspective view of the intelligent access control device.

Figure 1.2 is a rear perspective view of the intelligent access control device.

Figure 1.3 is a front elevational view of the intelligent access control device.

(Continued)

Figure 1.4 is a left side elevational view of the intelligent access control device, the right side elevation view being a mirror image, and

Figure 1.5 is a top plan elevational view of the intelligent access control device, the bottom plan elevation view being a mirror image thereof.

An intelligent access control device.
